ICE BUCKET

Arne Jacobsen, 403 Lyngbyve,
Gentofte, Denmark

Filed Sept. 30, 1968, Ser. No. 13,792

Term of patent 14 years

Int. Cl. D7—99

U.S. Cl. D44—1

FIG. 1.

FIG. 2.

FIG. 3.

FIG. 4.

FIGURE 1 is a perspective view of an ice bucket showing my new design;

FIGURE 2 is a side elevational view, with the handles in folded down position;

FIGURE 3 is a sectional view taken on line 3—3 of FIGURE 4; and

FIGURE 4 is a top plan view.

I claim:

The ornamental design for an ice bucket, as shown.
